UNITED STATES PATENT OFFICE.

ALBIN L. THOMA, OF PIQUA, OHIO.

DESIGN FOR A BADGE.

No. 39,499.

Specification for Design.

Patented Sept. 8, 1908.

Application filed May 28, 1908. Serial No. 435,573. Term of patent 14 years.

To all whom it may concern:

Be it known that I, ALBIN L. THOMA, a citizen of the United States, residing at Piqua, in the county of Miami and State of Ohio, have invented a new, original, and ornamental Design for Badges, of which the following is a specification, reference being had to the accompanying drawing, forming part thereof.

The figure is a perspective view, showing my new design.

I claim:

The ornamental design for a badge, as shown.

ALBIN L. THOMA.

Witnesses:

TREVA BARTMESS,
LOSH O. HARBAUGH.
